METHOD OF MAKING ABRASIVE ARTICLES

Milton F. Beecher, Holden, Mass., assignor to
Norton Company, Worcester, Mass., a corpora-
tion of Massachusetts

Application January 22, 1942, Serial No. 427,792

3 Claims. (Cl. 204—16)

1

The invention relates to abrasive articles and methods of making them, and more particularly to single layer diamond grinding wheels and points. The invention may be embodied in peripheral wheels, or in cup wheels grinding on an annular side face, or in articles of the nature of diamond dental drills, sometimes called dental points.

One object of the invention is to provide a simple and practical method for making abrasive articles of the types indicated. Another object of the invention is strongly to secure a single layer of diamonds to a metal backing. Another object of the invention is to make dental points giving long life. Another object of the invention is to make articles of the types indicated with a relatively close packing but even dispersion of the abrasive granules. Other objects will be in part obvious or in part pointed out hereinafter.

The invention accordingly consists in the features of construction, combinations of elements, arrangements of parts, and in the several steps and relation and order of each of said steps to one or more of the others thereof, all as will be illustratively described herein, and the scope of the application of which will be indicated in the following claims.

In the accompanying drawings showing three of many possible embodiments of the mechanical features of this invention,

Figure 1 is an axial sectional view of a mold and a backing therein, the backing being pressed into the mold by means of an hydraulic press;

Figure 2 is a view similar to Figure 1, showing a fragment thereof on an enlarged scale;

Figure 3 is a vertical sectional view showing an electroplating operation following the pressing operation of Figure 1;

Figure 4 is a plan view, on an enlarged scale, showing the diamonds located on a piece of open mesh cloth;

Figure 5 is an elevation of an hydraulic press, a movable table on a base, and a back for a peripheral wheel showing the step of pressing the diamonds into the back;

Figure 6 is a vertical sectional view of an electroplating bath showing the set-up for electroplating the peripheral wheel of Figure 5;

Figure 7 is a vertical axial sectional view of special apparatus for pressing diamonds into a

2

dental blank, showing also the platens of the hydraulic press which gives the pressure;

Figure 8 is a vertical sectional view of electroplating apparatus for securing the diamonds in position which were pressed into the blank as shown in Figure 7;

Figure 9 is a fragmentary sectional view, on an enlarged scale, of a wheel produced by the apparatus of Figures 1, 2 and 3;

10 Figure 10 is a fragmentary sectional view, on an enlarged scale, of the wheel produced by the apparatus of Figures 5 and 6;

Figure 11 is a fragmentary sectional view of a dental point produced by the apparatus of Figures 7 and 8.

Referring first to Figure 1, I provide a cup-shaped wheel back 20. This wheel back 20 is made of relatively soft metal or it will suffice if a flat annular surface 21 is a surface on a soft

20 metal portion. That is to say, the bulk of the wheel back 20 might be of any material provided a portion of it adjacent to the surface 21 is of soft metal. I provide a mold band 22 in which the back 20 fits with a sliding fit. I further provide a mold center 23 around which the back 20 also fits with a sliding fit, and a ring-shaped mold bottom plate 24 fitting between the band 22 and the center 23.

Referring now to Figure 4, in order to space 30 abrasive grains 25 preparatory to pressing them into the surface 21, I provide a piece of open mesh cloth 26. Bolting cloth is preferred. Bolting cloth is leno fabric with accurately spaced warp and weft. That is to say, the pick and sley

35 are held to very close tolerances. Leno cloth has certain ends in pairs and in the shedding one of each pair is moved over and to the other side of the other end of the pair. In this way the mesh is maintained. However, so far as the broad features of the invention are concerned, other open mesh cloth might be used and also closely woven cloth of any variety including cloth having nap, such as woolen or felt.

Nevertheless I prefer to use open mesh cloth 45 such as shown in Figure 4. This is first cut into the shape of a ring exactly to fit onto the upper surface of the bottom ring 24. Preferably it is glued in place, ordinary protein glue being satisfactory for this purpose, but any other adhesive 50 may be used. The cloth, therefore, provides a

grid for spacing the abrasive grains 25 which are preferably diamonds. If the cloth is adhesively secured to the ring 24, the openings therein may be larger than the abrasive grains. But if the cloth is not secured to the ring 24, the openings therein should be smaller than the abrasive grains 25 so as to obviate individual abrasive grains being covered by either warp or weft during the pressing operation.

After the mold parts have been assembled but before the back 20 is inserted, abrasive is spread upon the cloth 26 with a brush or in other suitable manner and with a little care it can be evenly dispersed upon the cloth 26 all around the circle. Then the mold parts are placed upon a bottom platen 30 of an hydraulic press and the back 20 is placed in position as shown. The press has a movable upper platen 31 which is now moved down against the back 20 with the desired pressure. If the back 20 or that part thereof adjacent the surface 21 is made of copper which is a good material for the purpose, a pressure of the order of five tons to the square inch is satisfactory. Aluminum is also a satisfactory metal in which to embed the diamonds and a pressure of about the same amount may be used. No definite figures for pressures can be given because the pressure depends upon the grit size of the abrasive and how deeply it is desired to embed the diamonds. The latter depends upon the cutting characteristics desired in the final product. If a free-cutting wheel is desired, the diamond abrasive should be but loosely embedded. If, on the other hand, long wear is desired, the diamond abrasive should be deeply embedded. The greater the pressure, the deeper will the diamonds be embedded and, on the other hand, the larger the diamonds the less will they be embedded.

After the pressing operation described, the upper platen 31 is raised and the back 20 is removed from the mold in the usual manner. In the ordinary case, the cloth 26 will not stick to the surface 21 impregnated with diamonds, but if it does it can be turned off or otherwise removed.

The back 20 with abrasive layer 35 is now stopped off. That is to say, a coating of stop-off 36 is deposited all over the back 20 excepting on the abrasive layer 35 and just below it. This may be done by providing a bath of molten stop-off and slowly lowering the back 20 into it, keeping the back on a vertical axis. Compositions for stop-offs are well known in the electroplating art, many of them having a base of paraffine.

Prior to depositing the coating of stop-off 36, the uncovered end 39 of an insulated wire 38 is welded or soldered to the back 20. The back 20 is now placed in a container 40 containing an electrolyte 41. I provide an anode 42 which is preferably a flat annulus of inside and outside diameters the same as the inside and outside diameters of the surface 35. A plurality of legs 43 are soldered to the anode 42 and extend radially outwardly and rest upon the top of the container 40 which is desirably made of glass. An uncovered end 44 of an insulated wire 45 is soldered or welded to one leg 43. The legs 43 may be stopped off, if desired; ordinary paint will serve for this purpose.

Wires 38 and 45 are now connected in circuit with a suitable source of direct current electricity for the purpose of electroplating a deposit of metal around the diamonds 25 of the layer 35 and onto the surface 21 where it is exposed. The

back 20 is the cathode in the electroplating cell. A suitable plating metal is nickel, because it tends to be electrodeposited under tension and it tends to form a strong union with the diamond grains. A solution of nickel sulphate on the acid side in water may be employed for the electrolyte 41. The anode 42 may be made of nickel in order to replenish the solution as the ions are precipitated therefrom, or this anode 42 may be made from an inert metal such as platinum which is not affected by the electrolytic action. I desire to form a strong plating securely holding the diamonds onto the back 20. For the manufacture of abrasive articles as contemplated by me, diamonds of the order of from 80 grit size to 500 grit size are preferably used. Assuming the largest of this range, most of the diamonds will be not substantially over one eightieth of an inch in the longest dimension and at least a quarter thereof will be below the surface 21. This leaves at the utmost a remainder of about .0125 of an inch of which it will suffice in most cases to cover half which is .0047 of an inch or a little over four and one-half thousandths. A good strong nickel plate of four and one-half thousandths thick can be formed and, moreover, in most cases the plate may be much thinner since ordinarily finer grits than No. 80 grit size will be used. Referring now to Figure 9, a fragment of the back 20, the diamonds 25 and the electroplated layer 50 are shown. For producing a strong electroplate 50, a nickel anode and a nickel sulphate electrolyte may be used, as stated, and the known procedure of the electroplating art should be employed so far as electromotive force, current, density, space of anode and cathode and the like are concerned. It may be noted that it is preferable to use a low current density at first, for example of the order of one or two amperes per square foot of the surface to be plated, and to continue that low density for a short time, such as about an hour. Thereafter the current density may be gradually increased up to around ten amperes. At the start, the electromotive force may be 4 to 8 volts. The foregoing is to be taken as descriptive and in no way limiting the invention. Other metals may be used to form the plating 50 and other electrolytes may be used.

Referring now to Figure 5, for the manufacture of peripheral wheels having a soft metal disk backing 60, I provide the same hydraulic press having bottom platen 30 and top platen 31. I further provide a base 61 having on the upper side, slideways 62 on which rests a sliding table 63. The slideways 62 are spaced apart. Between them is located a nut 64 integral with the table 63. Through the nut 64 passes a screw shaft 65 supported in a bearing 66 near one end of the base 61 and supported in a thrust bearing 67 formed in a plate 68 attached to the other end of the base 61. A hand wheel 69 is fastened to the screw shaft 65 and serves to turn it. When the hand wheel 69 is turned, the table 63 is moved along the base 61 on the slideways 62.

To the top of the table 63 which is flat I glue some cloth 26 and upon the cloth 26 I locate diamonds 25, as already described. The table 63 is first withdrawn to one end of the base 61. The base 61 is then placed upon the lower platen 30 so that most of the table 63 is to one side of the upper platen 31. The wheel 60 is now placed near one end of the table 63 and near one edge of the upper platen 31, approximately as shown in Figure 5, and the upper platen 31 is brought down. Interposed between the platen 31 and the wheel

60 is a strip 70 of somewhat soft metal. This metal should be harder than the material of the wheel back 60 but not too hard. The table 63 may be of the same metal. For example, if the wheel 60 is copper, the strip 70 and the table 63 may be of soft steel. The table 63 is now traversed by rotating the hand wheel 69. The table 63 should be at least π times the diameter of the wheel 60 and the strip 70 should be the same length and, of course, throughout its entire distance backed up by the platen 31. Naturally, these parts should be a little longer than the minimum distance to provide a small margin at each end of the stroke.

The hydraulic press is caused to exert sufficient pressure to press the diamonds into the copper back 60. Naturally when the wheel 60 has rotated 180 degrees, the diamond-covered portion will come in contact with the strip 70 and will continue in contact with the strip 70 until the full revolution has been made. This is why the strip 70 must be not too hard, else it may break the diamonds already embedded; yet harder than the backing 60, else the diamonds may be transferred to the strip 70 which is not desired. The same considerations apply to the table 63 (or its upper surface) and, indeed, also to the mold bottom plate 24 of Figure 1.

Referring now to Figure 6, after the diamonds have been embedded in the periphery of the disk 60, the back 60 has the end of a covered wire 71 soldered thereto, is stopped-off by a stop-off 73, 74, is placed in an electroplating tank 75 with electrolyte 76 inside of an anode 77 provided with a lead-in wire 78, and the periphery of the wheel 60 is electroplated in the same manner as already described and for the same purpose. Figure 10 is illustrative of the final product and shows the back 60, the diamonds 25, and plating layer 50. Many different metals can be used for plating but, as previously stated, nickel is preferred.

I show in Figures 7 and 8, the technique of the invention applied to the manufacture of dental points. Referring to Figures 7 and 8, a blank for a dental point comprises a shank 80 having a notch 81 at one end and a conical portion 82 at the other end. A press with bottom platen 30 and upper platen 31 is shown in Figure 7. I provide a fixture comprising a bottom bevelled ring 85 of soft steel, and a top bevelled ring 86 of soft steel 87 on one side and of hard steel 88 on the other side. In the hard steel portion 88 is an annular groove 89 containing gearing balls 90. These also fit in an annular groove 91 in a hard steel ring 92. I cut some of the cloth 26 to fit part way around on the upper surface of the ring 85 and fill the interstices with diamonds, as previously described. The conical portion 82 of the dental point is of soft metal, for example, German silver. The upper ring 86 is spaced from the lower ring 85 by means of conical rollers 93 as well as by the conical portion 82. Preferably there should be two of the spacing conical rollers 93, and these as well as the conical portion 82 are locked in position by a guard ring 95. The result is that when the upper ring 86 is turned, the diamonds will be embedded in the conical portion 82, as in the other embodiments of the invention. The ring 86 may be turned if the pressure is applied by a long handle 95 having a reduced portion 96 screwed into the composite ring 86. The bevelled rings and the cones should be of such dimensions and angles that the large diameter of the cone 82 is to the small diameter thereof as the large diameter of the bevelled rings is to the small diameter thereof.

The electroplating apparatus is shown in Figure 8 and involves an anode 100 with lead-in wire 101, a hub 102 to support the shank 80, the hub 102 having a spring latch 103 which fits in the notch 81, and the hub having three spokes 104 which may be 120 degrees apart to support it upon the glass container 105 for the electrolyte 106. The lead-in wire 107 is secured to one of the spokes 104, as in the other embodiments of the invention. Without further description, it will be seen that a good deposit of metal may be electroplated around the diamonds 25 to hold them securely in place upon the conical portion 82. The final product is shown in Figure 7 which is self-explanatory.

It will thus be seen that there has been provided by this invention an article and a method in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

I claim:

1. In a method of making abrasive articles, the steps which comprise utilizing the pattern formed by the warp and weft of a leno cloth to provide a grid for distributing diamond abrasive particles substantially evenly according to the grid-like pattern of the cloth, pressing a metal back and said diamond particles together with a pressure sufficient to embed the individual particles in the metal of the back and thereby distribute them throughout the surface of the back substantially

30 the same as they are held distributed by said pattern of said cloth, separating the cloth from the metal back and diamond particles assembly, and then electroplating a deposit of metal upon the exposed portions of the surface of the metal back and around portions of the diamond particles protruding therefrom to co-act in holding them assembled to the metal back.

2. The steps in a method of making diamond abrasive articles which comprise placing a ring of bolting cloth upon a ring of relatively hard material, distributing diamond particles upon said bolting cloth, pressing a back made of metal that is softer than the hard material of said first-mentioned ring against the diamond particles with a pressure sufficient to embed them in the metal of said back, separating the bolting cloth from the back and diamond particles assembly, then securing a layer of metal to the exposed portions of the surface of the metal back and around protruding diamond particles to co-act in holding them in position.

3. In a method of making abrasive articles, the steps which comprise utilizing the pattern formed by the warp and weft of a leno cloth to provide a grid for spacing diamond abrasive particles, pressing a metal back and said diamond particles together with a pressure sufficient to embed the individual particles in the metal of the back and thereby distribute them throughout the surface of the back substantially the same as they are held distributed by said leno cloth, and then separating the cloth from the metal back and diamond particles assembly.

MILTON F. BEECHER.
